UNITED STATES PATENT OFFICE.

JOHN C. COCHRAN AND SAMUEL A. WILLIS, OF BROOKLYN, NEW YORK; SAID WILLIS
ASSIGNOR TO SAID COCHRAN.

STATION-INDICATOR.

1,316,353.

Specification of Letters Patent. Patented Sept. 16, 1919.

Application filed December 1, 1916. Serial No. 134,317.

To all whom it may concern:

Be it known that JOHN C. COCHRAN and SAMUEL A. WILLIS, citizens of the United States, residing at Brooklyn, in the county 5 of Kings and State of New York, have invented certain new and useful Improvements in Station-Indicators, of which the following is a specification.

This invention relates to improvements in 10 indicating mechanism and particularly to mechanism for exposing successive indications in predetermined order. A preferred embodiment of the general invention is employed in connection with the indicating of 15 stations and the present disclosure is based on such use without however restricting the invention to such particular use.

Various forms of apparatus for this purpose have heretofore been employed, one 20 type employing a web structure and operating mechanism which is designed to move the web back and forth relative to a sight opening through which a particular indication is exposed, the web being moved intermittently by suitable means, as by the manipulation of an operator at will or through 25 connections which will provide for an automatic movement. The present invention pertains more particularly to this general 30 type. In such devices it is the general practice to employ a pair of spools to which the ends of a web are connected. During the operation the web is led from one spool to the other until the end of the route is 35 reached, whereupon the mechanism is manipulated to return the web to the initial spool.

In such devices, and especially where the route includes a comparatively large number 40 of stations, necessitating the use of a web of considerable length, the variations in the diameter of the roll due to the adding to or removal of the successive convolutions of the web, offer material difficulties to the 45 proper operation of the mechanism. This difficulty increases where the web is of somewhat fragile character as where ordinary paper material is used for the web, there being a constant tendency to disrupt the 50 strip under the drawing action of the mechanism in providing the travel of the web, excepting possibly under conditions where the spool from which the web is being unwound is left free, which in turn provides 55 disadvantages in that the operation of the

mechanism intermittently will tend to produce an overrunning action and thus affect the proper positioning of the indication in the rear of the sight opening, as well as providing other obvious disadvantages. 60

Attempts have been made to meet this particular condition by varying the spacing of the indications on the web. While this may tend to overcome some of the objections where used in connection with a web of material sufficient to withstand the drawing tensions, etc., other difficulties are such as to materially affect the proper feed of the web. 65

The present invention is designed more 70 particularly to meet these various objections and at the same time permit the use of webs of any desired length and, if desired, of the ordinary paper type, the structure being such as to provide for proper winding and 75 unwinding action without the presence of drawing strains on the web and at the same time provide against overrunning; in addition, the construction provides for equal spacing of the indications on the web, eliminating the difficulty presented by reversal 80 in direction of wind and unwind of the web with the resultant variations in roll diameters. 85

The invention also contemplates the substitution of arbitrary indications, such for instance as numerals, for the usual name-designated indications of stations.

The invention, in addition to these general objects, is designed to provide for simple and efficient operation, improved take-up and let-off mechanism, structure compact in form, durable in construction and which can be manufactured and installed at minimum cost. 90

To these and other ends, the nature of which will be readily understood as the invention is hereinafter disclosed, said invention consists in the improved construction and combination of parts hereinafter fully 95 described, illustrated in the accompanying drawings, and more particularly pointed out in the appended claims.

In the accompanying drawings, in which similar reference characters indicate similar parts in each of the views,—

Figure 1 is a perspective view of the indicator complete.

Fig. 2 is a central vertical sectional view.

Figs. 3, 4 and 5 are sectional views taken 110

on the lines 3—3, 4—4 and 5—5 respectively of Fig. 2, parts of these views being shown in elevation.

Fig. 6 is a front elevation of internal parts, the casing being shown in section.

Figs. 7 and 8 are detail views showing different positions of the actuating mechanism for the web support.

Fig. 9 is a detail view of a stop mechanism. 10 Fig. 10 is a longitudinal sectional view of one of the spools, a portion of the frame of the mechanism being included.

Fig. 11 is a sectional view taken on line 11—11 of Fig. 10.

15 Fig. 12 is a fragmentary detail view showing a portion of the mechanism for locking the web against advance movement.

Fig. 13 is a view showing a portion of a chart employed in connection with the mechanism. 20

In the drawings, 15 indicates a casing having a rear wall 15^a and bottom 15^b to which the operating mechanism is secured, and 16 indicates a removable cover having a sight 25 opening 17 at its front, the latter preferably being closed by a glass plate 17^c through which the desired indication is to be exposed. Obviously, other well known types of apparatus for rendering an indication 30 prominent may be employed. As shown in Fig. 1, the cover may carry a permanent indication, such as "Next station," although this is unessential. The cover and casing are connected in any suitable manner so as 35 to inclose the mechanism, suitable openings 15^e being left in the bottom for the passage of actuating cords, or other operative mechanism presently referred to.

40 Mounted on the bottom 15^b, and secured to the back 15^a is a frame composed mainly of side plates 18^a, spacing bars 18^b, and a plate 18^c, these parts fixedly locating the two side plates parallel with each other, these plates carrying substantially the entire operating mechanism.

Secured to the inner side of each plate 18^a 45 is a bracket 19. 20 designates a shaft which extends laterally of the mechanism and through brackets 19, being supported there- 50 in by sleeves 21 mounted loosely on the shaft and carried by the brackets, each sleeve carrying an arm 22 on the outer side of the bracket, and a sector 23 inside of the bracket. The sleeve 21 and the parts carried thereby 55 are held in normal position by a spring 24 preferably of the convolute type, with one end connected to the sleeve and the opposite end connected to the bracket. Each sleeve is independently movable rotatively on the 60 shaft and each is adapted to be given rotative movement by means of cords 25 which are secured to the respective sectors and are carried downwardly through openings 15^e, these cords forming a simple type of actuating devices for the structure, as presently 65

described. Each sector is preferably provided with a cord-receiving groove 23^a within which the cord rests and which forms a guiding element therefor. Additional guides 26 are mounted on posts 26^a projecting inwardly from the side plates 18^a. The sectors and the connections of the operating cords therewith are so arranged that when one cord is drawn downwardly, the sector to which it is connected is moved in one direction of rotation against the tension of its spring 24. The other sector and its cord remains inactive during such movement, being adapted when operated, to rotate in the opposite direction, the springs 24 being adapted to return the sectors to their normal positions when the cords are released. 75

Mounted at each end of shaft 20 outside of arms 22 are spacing members 27 which are adapted to position wheels 28 from arms 22, said wheels being secured to shaft 20 in suitable manner. Wheels 28 are provided on their peripheries with teeth 28^a, these teeth being adapted to coöperate with perforations ^a carried by the web ^a. The opposite ends of the web are carried by spools 29, previously referred to, these spools being adapted to carry the wound convolutions of the web, the latter extending around stationary member 30 and over wheels 28, as shown 95 more clearly in Fig. 5, the teeth 28^a entering the perforations ^a of the web.

The movements of the web are provided by the oscillating movements of sectors 23, this action being obtained through operating connections located between arms 22 and wheels 28. 100

Each wheel 28 is provided with a plurality of pins 31 projecting inwardly at uniformly spaced points of the wheel in such 105 locations as to be within the path of movement of a pawl 32 pivoted on arm 22.

As shown in Figs. 3 and 7, pawl 32 is normally located in proximity to one of the pins 31 (preferably the lowermost one), the normal position of the operating sector of the pawl being shown in Fig. 3, in which the pawl is shown as in contact with a stop 32^a carried by the bracket; pawl 32 also carries a shoulder 32^b, which coöperates with a stop 32^c carried by arm 22, and in the normal position of Fig. 3, this shoulder is shown as spaced from stop 32^c, the pawl being held in this position by a spring 32^d. When one of the operating cords 25 is drawn downwardly, as for instance, the cord of Figs. 7 and 8, the initial action is to start the rotation of sector 23, thus moving arm 22 counter-clockwise in Fig. 7, thus permitting spring 32^a 110 to shift pawl 32 on its pivot to bring shoulder 32^b into contact with stop 32^c thus causing the pawl to slightly shift to bring its toe into the path of and behind the particular pin which is immediately in advance 115 of the pawl. After contact of pawl and pin 120

125 130

is had during such movement of the cord, continued movement of the cord in the same direction will cause arm 22 to continue this counter-clockwise motion and carry with it the wheel having the pin which is engaged by the pawl. The completion of this movement is shown in Fig. 8, in which the arm 22 is shown as having been brought into contact with a stop 33 carried by the bracket, 5 thus limiting the further travel of the arm and the movement of wheel 28. When the cord is released, spring 24 returns the sector 23 to its normal position by a clockwise movement in Figs. 7 and 8, this return movement bringing the pawl into contact with the succeeding pin 31, and since the pawl is free to move pivotally, said pawl will slip by such succeeding pin and pass to the position shown in Fig. 3, placing the parts in 10 position for another operation or for a reversal operation by the other sector in case the other cord is the one drawn. As both wheels 28 are mounted on shaft 20, it will be readily understood that this movement 15 in one direction of the wheel is communicated to the other wheel by shaft 20, said shaft rotating freely in sleeve 21 of the inactive sector, the two wheels and the shaft forming a rotatable support for the web. 20 Stop 33 acts to limit the travel of arm 22 in advancing the wheel. To limit the return movement of the sector under action of spring 24 we provide a stop 34 carried by the bracket, arm 22 contacting with this stop 25 in the normal position of the sector, as shown in Fig. 3. 30

As will be understood, this limitation of travel of a sector limits the length of travel of wheels 28, and since the driven wheel 28 must be moved a distance sufficient to place the succeeding pin in proper position to be engaged by the pawl, the full stroke of the sector is to be given at each manipulation; should the movement be of less length, the 40 succeeding pin would not be brought into proper position. Should this occur, the cord is again manipulated causing arm 22 to travel without pawl engagement with a pin until the parts have been brought to the position left by them at the end of the preceding movement, whereupon the stroke can be completed, thus placing the parts in proper position. Hence there is provided a wheel travel movement of definite length with each 45 actuation of a sector, and since the web travels with wheels 28 by reason of the teeth and perforation connection therebetween, it will be understood that the web will be caused to travel a definite distance relative to the sight glass with each operation, thus enabling the indications, indicated at α^2 , to be spaced apart equidistant on the web. 50 Stop 33 will act to limit the travel of arm 22 in the advancing direction. However, 55 this stoppage of the arm is ineffective on the

travel of wheels 28. In order, therefore, to prevent any overrunning action at this point, we employ stop mechanism effective on such wheel, this mechanism being shown as a bell crank lever 35 pivotally carried by a bracket 70 19, one arm of the lever being arranged to coöperate with a shoulder 36 carried by wheel 28, the arrangement preferably being in the form of a flange 37 having its periphery provided with shoulders or stops 36, 75 a preferred form placing a portion of the periphery in advance of the shoulder in the form of a cam against which said end of the lever will ride when released. One arm of lever 35 extends within the path of travel 80 of arm 22, said arm, when in normal position, moving lever 35 on its pivot against the tension of spring 35^a, thus removing the toe of the other arm out of contact with flange 37 and out of the path of shoulder 36, 85 permitting the operation of the sector previously described. As arm 22 advances during the operation herein described, spring 35^a moves lever 35 on its pivot until the engaging toe of the lever again contacts with 90 flange 37, thus placing this toe in the path of travel of shoulder 36 with which it preferably engages concurrently with contact of arm 22 and stop 33, thus preventing any overrunning action of wheels 28. Since this 95 position of lever 35 is not changed until arm 22 again contacts with the lever, it will be understood that the web will be held from changing its position until this lever has been moved by arm 22. 100

The connections between the several arms 22 and wheels 28 are similar, the parts being so arranged that, regardless of which cord is actuated, the relation of pins 31 and of the pawls is the same upon the completion 105 of the cycle of sector movements, thus enabling either cord to be actuated at will, the particular cord employed determining the direction of movement of the web.

38 designates members carried by the side 110 plates 18^a projecting laterally thereof to form passageways within which the edges of the web travel to and from the spools.

As will be readily understood, a web of a length sufficient to contain a comparatively 115 large number of indications, as, for instance, is required in indicating stoppage points for stations on a railway or streetcar system, with the indications of sufficient size as to be easily read by an observer, will 120 provide a comparatively large number of convolutions on spools 29, these convolutions increasing and decreasing in number as the web is shifted from one spool to the other, one spool acting as a take-up roll 125 while the other acts to let off the convolutions as the web travels. Since the peripheral speed of a roll varies in proportion to its diameter, it will be readily understood that with a peripheral speed of both rolls 130

equal to each other the rotational speed of the wheel will vary with the variation in such diameter. There is a constant change in the relation of periphery and rotational speed of the spool acting as the takeup roll, and as the rotational speed is, for structural reasons, made uniform, provision is made to automatically compensate for this change in relation by providing a yielding connection between that portion of the spool carrying the web and the portion which is positively driven.

This construction is shown more particularly in Figs. 10 and 11 in which 39 indicates a shaft carrying a sleeve 40, the latter having enlargements 40^a. Said enlargements are provided with spring supported members 41, preferably projecting radially from the enlargements into contact with the interior of the cylindrical spool 29 and frictionally engaging said spool. If shaft 39 be driven at a constant speed, the frictional engagement will tend to cause the spool to rotate in unison therewith as long as the resistance provided by the web is not greater than the friction developed by members 41. Since the spool is not required to act as a web-drawing element, the friction may be comparatively light, thus permitting any increase in resistance to produce a relative slip action between members 41 and the spool without placing material strain on the web.

Owing to the fact that the direction of travel of the web is reversible, thus shifting the take-up action from one roll to the other, both spools must be capable of being positively driven, and since the let-off spool must permit of free let-off action, the connection between shaft 39 and its drive is provided by a pawl and ratchet connection between the drive, represented by sprocket wheel 42, and shaft 39, the ratchet wheel being indicated at 43 and pawl at 44. As shown in Fig. 4, the ratchet mechanisms of the two spools operate in opposite directions. Both of the sprocket wheels 42 are driven in synchronism by endless sprocket chain 45, which also engages the teeth of sprocket wheel 46 mounted on shaft 20, a chain tightening device 47 being provided in order that proper action will be had.

As shown in Fig. 10, ratchet 43 is secured to and rotates with shaft 39, while sprocket 42 is loosely mounted on the shaft and carries a member 42^a on which pawl 44 and its actuating spring 44^a is mounted. The opposite end of shaft 39 projects through the opposite side plate 18^a and preferably is held against endwise movement by a tension member 48 contacting with the end of the shaft, the tension member preferably having means for adjusting the tension.

By this arrangement, positive compen-

sating action will be had irrespective of the direction of travel of the web. For instance, assuming travel of the web counter-clockwise in Fig. 4, thus winding the web on the spool at the left of Figs. 4 and 5, sprocket wheel 42 at the left will be driven counter-clockwise thus moving its pawl 44 in the same direction and causing this shaft 39 to be positively driven in such direction. This produces a substantially constant rotational speed of the shaft and enlargements, and since the peripheral speed of member 29 remains the same, the variations in diameter produced by the added convolutions provide the relative slip or differential movements between the shaft and spool 29, thereby maintaining the web leading to the spool taut without, however, placing any undue strain on the web or acting to draw the web in such manner as to shift the position of wheels 28.

During this operation the web is unwinding from the spool at the right in Figs. 4 and 5, the movements of wheels 28 tending to draw the web from this spool. The sprocket of this spool is also traveling counter-clockwise and is positively driven by chain 45, but the decreasing diameter of the convolutions on this spool does not affect a slip action at the friction mechanism, the relation between the periphery and rotational speeds of this structure being overcome in the ratchet-mechanism. During the let-off operation the cylindrical spool 29 acts as a drive member for shaft 39 through the frictional connection, ratchet wheel 43 traveling with the shaft. At the same time the pawl is being moved by the positive drive of sprocket 42 of this roll, and the parts are so arranged that during this action the travel of the pawl is at a slightly greater speed than that of the ratchet with the result that a relative movement between pawl and ratchet will be present.

As a result, the general relation of pawl and ratchet is maintained, but at the same time the web is drawn off of the spool without material resistance. In addition, overrunning of this spool by the drawing of the web is prevented for the reason that this would increase the speed of travel of the ratchet to a point greater than the speed of travel of the pawl, thereby driving the adjacent tooth of the ratchet into contact with the pawl and immediately stopping this overrunning action, the greatest amount of overrunning travel being the length of a single tooth.

It is to be understood, of course, that the parts are so proportioned that the operations referred to will be produced. For instance, the proportions may be such that the pawl and ratchet of the spool being unwound travel at equal speeds when both spools are

carrying approximately the same number of convolutions. This, of course, may be varied as desired.

As shown in Fig. 6, we preferably employ 5 rollers 49 carried by brackets 50 for the purpose of insuring a proper engagement of teeth 28^a and perforations a', rollers 49 being shifted as shown to permit of the travel of teeth 28^a while the web is forced 10 into contact with the periphery of the wheel.

Since, during the unwinding action, shaft 39 of the spool being unwound is traveling in the direction of unwinding movement, the drawing strain on the spool is reduced to a 15 minimum, it being required only to take care of the variations in movement, the slight resistance between the ratchet wheel and its pawl being immaterial.

It will therefore be readily understood 20 that the compensating structures enable operation to be had with substantially no drawing strains or overrunning effect, thus enabling the web to be maintained in a substantially taut condition.

25 The web is secured to the spools in any desired manner, and to prevent undue strain on such connection we preferably employ a locking mechanism which automatically acts to limit the travel of the web beyond the 30 safety point. This is provided by projecting a pin 50' into the path of arm 22 which is being moved to provide the web travel. Said pin is carried by a pivoted lever 51 (Figs. 2 and 12), said lever being connected 35 to a rod 52 extending between the brackets and capable of longitudinal movement. The structure is in duplicate, as shown in Figs. 2 and 5, each rod carrying a yielding abutment 53 at a proper point. 54 indicates a 40 member carried by shaft 20 and having recesses 54^a to receive rods 52. Member 54 is movable in the direction of length of shaft 20 by a threaded connection therewith. As a result, member 54 will be moved back and 45 forth between abutments 53 through the movement of the shaft under the sector operations heretofore described. This threading action gradually moves member 54 into contact with the abutment located in its 50 path of advance movement, further movement shifting the rod on which the abutment is mounted, to actuate lever 52 and project the pin into the path of movement of arm 22 to prevent further web movement 55 in this direction. This acts to lock the mechanism against continuing movement without placing any strain on the web. The direction of web travel is then reversed, member 54 moving in the opposite direction 60 and withdrawing pin 50 from its locking position. Abutments 53 may be adjustable on the rods, thus permitting variation in the total length of travel of the web.

While the structure thus described is 65 adapted to provide the step by step move-

ment to the web, with each step of equal length, and the casing structure is so arranged as to prevent access to the mechanism excepting by manipulating such casing, the operating mechanism is so arranged 70 that the mechanism for driving the web in this manner is normally maintained out of engagement with the web support and spools excepting during periods when sector movement is being had. At other times, the web- 75 supporting structure and the spools are free to be moved to enable shifting of the web manually in either direction by operating, for instance, the chain structure 45. Since this chain connects the web support and 80 spools, and the compensating mechanism is active during the movement of the chain, such shifting action can be had when desired by removing casing structure.

If desired, we may employ signaling mechanism, such, for instance as a gong 55 to indicate when a change is made in the indication. An operating mechanism therefor is shown in Fig. 3, in which 56 indicates a striker having a toe 56^a and normally held 85 in a neutral position by springs 57 and 58. 59 indicates a sliding member carrying a pivoted lever 60 the latter having a shoulder 60^a adapted to coöperate with toe 56^a. The upper end of member 59 is formed with a 90 cam-like face 59^a which is located in the path of travel of pins 61 (which may be continuations of pins 31 projected on the opposite side of wheel 28). A spring 62 tends to maintain member 59 in its upper 95 position, pin 61 moving the member downwardly during the latter portion of the travel of wheel 28. Spring 63 tends to move lever 60 toward striker 56, this movement being controlled by the coaction of a pin 100 64 and the lever.

The inactive position of the parts is shown in Fig. 3. At the beginning of the sector movement pin 61 passes out of contact with face 59^a, permitting member 59 to move 110 upward under the action of spring 62. Member 59 raises lever 60 which is thus freed from contact with pin 64, spring 63 moving shoulder 60^a above toe 56^a. As the sector approaches the end of its travel the 115 succeeding pin 61 contacts with face 59^a moving member 59 downwardly. During this movement coaction between shoulder 60^a and toe 56^a moves the structure to place spring 58 under tension. When lever 60 120 again passes into contact with pin 64, the downward movement causes the lever to be gradually moved away from the striker under the action of pin 64, and when this movement reaches a point where shoulder 125 60^a passes out of contact with toe 56^a, the tension of spring 58 becomes effective to throw the striker outwardly into contact with the gong against the action of spring 57, the latter then becoming effective to re- 130

turn the striker to neutral position. The completion of this movement places the signaling mechanism in its inactive position ready for the succeeding operation.

5 The indicating mechanism thus described is adapted for use in various relations, but has its preferred embodiment employed in connection with indications which are arbitrary in character, such for instance as 10 numerals or indications of an equivalent type, thus enabling the use of mechanism which is compact and comparatively narrow in width, occupying but little space in the car, while making the indications of a size 15 easily read from any portion of the car.

When used in this form as a station indicator, stations are each given an arbitrary indication, successive stations having the successively-arranged arbitrary indications.

20 When so arranged, we preferably provide schedules or charts which interpret the application of the arbitrary indications to the names of the stations, these charts or schedules being posted at suitable points accessible 25 to the traveling public so that the relation may be readily determined.

This arrangement provides a number of advantages. For instance, a daily traveler quickly learns the particular indication 30 which represents his station. As the preferred embodiment contemplates the use of successive numerals, inspection of the exposed indication will quickly inform the traveler of the approximate number of stations 35 distant from his home station at any time, without being required to learn the particular order of stations on the route traveled. Another advantage results from the fact that similar indications may be 40 employed for a number of different routes, in which case a car may be shifted from one route to another without rendering the indicator useless or without requiring a change in the web. When this course is pursued, 45 the chart or schedule preferably indicates the various routes and the particular relation between the arbitrary indications and the stations of each route.

A fragmentary arrangement of a chart of 50 this type is shown at B in Fig. 13.

While we have shown the actuating mechanism in the form of cords adapted for manual operation, it is to be understood that this showing is simply by way of example, it 55 being readily understood that cords 25 may be replaced by other structures for manual manipulation or for connection to mechanism which will automatically provide the sector action at predetermined points, such 60 actuating mechanism being well known in the art.

While we have herein shown and described a preferred construction and arrangement of parts, and a preferred manner of using 65 such construction, it will be readily under-

stood that variations or modifications therein may be required or desired to meet the exigencies of use, and we therefore desire it to be understood as reserving the right to make any and all such changes or modifications as may be found necessary or desirable in so far as the same may fall within the scope of the invention as expressed in the accompanying claims; and it is further understood that the invention is not limited to 75 the particular use referred to but may be employed in other connections where the conditions of use are of the same general type as those indicated herein.

What we claim is:

1. In combination, a web, a pair of spools to which the web is secured and on which it is wound and unwound, a rotatable support on which the web travels, means for driving said support step by step in either direction of rotation, and means independent of the action of the driving means for automatically locking the support against advance movement, said means being operative at a predetermined point in the travel 90 of the web, whereby the connection between the web and the spool will be maintained free from drawing strains.

2. In combination, a web, a pair of spools to which the web is secured and on which it is wound and unwound, a rotatable support on which the web travels, means for driving said support step by step in either direction of rotation, and means for automatically locking the support against advance movement, said means being operative at a predetermined point in the travel of the web, whereby the connection between the web and the spool will be maintained free from drawing strains, said locking means 105 being rendered active and inactive by the movements of the rotatable support.

3. In combination, a web, a pair of spools carrying the web, a rotatable support over which the web travels, a means for rotating 110 the support, means for moving the web operated by the rotation of the support, signal mechanism and means operated by the rotation of the support to actuate the signal mechanism.

4. In combination, a web, a pair of hollow spools carrying the web, a rotatable support over which the web travels, means for rotating said support, a driving element for each spool, means for rotating said driving elements actuated by the rotation of the support and frictional driving means between said driving elements and the spools at points within the hollow portion of each spool and beneath the location of the web 125 carried by the spool.

5. In an apparatus of the character described and in combination, a web, a pair of spools to which the web is secured and on which it is wound and unwound, a rotatable 130

- support over which the web travels, said support including a pair of spaced-apart axially-aligned wheels mounted to operate in synchronism, and means for moving said support step-by-step in either direction of rotation, said means including independent mechanisms for and adapted to coöperate with each wheel for moving the support, each of said mechanisms being adapted to provide support-movements in a single direction, said mechanisms and the wheels being operatively engageable solely during mechanism movements, whereby said web may be moved independently of said actuating mechanisms.
6. In an apparatus of the character described and in combination, a web, a pair of spools to which the web is secured and on which it is wound and unwound, a rotatable support over which the web travels, said support including a pair of spaced-apart axially-aligned wheels mounted to operate in synchronism, and means for moving said support step-by-step in either direction of rotation, said means including independent mechanisms for and adapted to coöperate with each wheel for moving the support, each of said mechanisms being adapted to provide support-movements in a single direction, said mechanisms and the wheels being operatively engageable solely during mechanism movements in one direction, whereby said web may be moved independently of said actuating mechanisms.
7. In an apparatus of the character described and in combination, a web, a pair of spools to which the web is secured and on which it is wound and unwound, a rotatable support over which the web travels, said support including a pair of spaced-apart axially-aligned wheels mounted to operate in synchronism, and means for moving said support step by step in either direction of rotation, said means including an oscillatory element having an arm and a member for moving said arm, a pawl carried by said arm and yieldable in one direction, and pins carried by one of said wheels within the path of travel of said pawl, the movements of said arm in one direction engaging the pawl and a pin to drive the support in web-advancing direction, the movement of said support positioning a succeeding pin in the path of travel of the pawl, and stop mechanism for limiting the oscillating movements of said elements, the relative positions of said pins being determined by the length of support movement.
9. In an apparatus of the character described and in combination, a web, a pair of spools to which the web is secured and on which it is wound and unwound, a rotatable support over which the web travels, said support including a pair of spaced-apart axially-aligned wheels mounted to operate in synchronism, and means for moving said support step-by-step in either direction of rotation, said means including an oscillatory element having an arm and a member for moving said arm, a pawl carried by said arm, and having a lost-motion relation thereto, pins carried by one of said wheels and adapted to coöperate with said pawl in the advancing movements of the support, and a spring adapted to maintain said pawl in one of its lost-motion positions, whereby said pawl is normally out of the path of movement of said pins.
10. In an apparatus of the character described and in combination, a web, a pair of spools to which the web is secured and on which it is wound and unwound, a rotatable support over which the web travels, said support including a pair of spaced-apart axially-aligned wheels mounted to operate in synchronism, and means for moving said support in either direction of rotation, said means including an oscillatory mechanism for moving said support in one direction, stop mechanism for limiting the length of each of such movements of the oscillatory mechanism, and means rendered active and inactive by such oscillatory movements for limiting the movement of the support.
11. In an apparatus of the character described and in combination, a web, a pair of spools to which the web is secured and on which it is wound and unwound, a rotatable support over which the web travels, said support including a pair of spaced-apart axially-aligned wheels mounted to operate in synchronism, and means for moving said support in either direction of rotation, said means including an oscillatory mechanism for moving said support in one direction, stop mechanism for limiting the length of each of such movements of the oscillatory mechanism, and means rendered active and inactive by such oscillatory movements for limiting the movement of the support, said

- latter means including spaced apart abutments carried by a wheel, and a bell crank lever normally held out of the path of movement of said abutment by said oscillatory mechanism and movable into such path by the movement of the support.
12. In an apparatus of the character described and in combination, a web, a pair of spools to which the web is secured and 10 on which it is wound and unwound, a rotatable support over which the web travels, said support including a pair of spaced-apart axially-aligned wheels mounted to operate in synchronism, and means for moving 15 said support in either direction of rotation, said means including an oscillatory mechanism for moving said support in one direction, stop mechanism for limiting the length of each of such movements of the oscillatory 20 mechanism, and means rendered active and inactive by such oscillatory movements for limiting the movement of the support, said latter means including spaced apart abutments carried by a wheel, and a bell crank 25 lever normally held out of the path of movement of said abutment by said oscillatory mechanism and movable into such path by the movement of the support, said abutments being relatively positioned to provide 30 engagement of an abutment and said lever concurrently with the activity of the stop mechanism in limiting the oscillatory movement.
13. In an apparatus of the character described and in combination, a web, a rotatable support over which the web travels, means for moving said support step by step in either direction of rotation, a pair of rolls to which the web is secured and on 35 which it is wound and unwound, each roll including a shaft and a web-supporting spool concentrically arranged and relatively movable rotatively, friction mechanism between said shaft and said spool and rendered 40 active at spaced points in the length of the spools, and operative connections between 45 said support and said shaft.
14. In an apparatus of the character described, and in combination, a web, a rotatable support over which the web travels, means for moving said support step by step in either direction of rotation, a pair of rolls to which the web is secured and on which it is wound and unwound, each roll 50 including a shaft and a web-supporting spool concentrically arranged and relatively movable rotatively, friction mechanism between said shaft and said spool and rendered active at spaced points in the length of the 55 spools, and operative connections between said support and said shaft, said connections including a drive element loosely mounted on each shaft, and pawl and ratchet mechanism connecting said drive element and its 60 shaft.
15. In an apparatus of the character described, and in combination, a web, a rotatable support over which the web travels, means for moving said support step by step in either direction of rotation, a pair of 70 rolls to which the web is secured and on which it is wound and unwound, each roll including a shaft and a web-supporting spool concentrically arranged and relatively movable rotatively, friction mechanism between 75 said shaft and said spool, and rendered active at spaced points in the length of the spools, and operative connections between said support and said shaft, said connections including a drive element loosely mounted on each shaft, and pawl and ratchet mechanism connecting said drive element and its 80 shaft, the pawl and ratchet mechanism of one roll being inactive during the activity of the similar mechanism of the 85 other roll.
16. In combination, a web, a pair of spools to which the web is secured and on which it is wound and unwound, a rotatable support on which the web travels, means including a pair of arms for driving said support step by step in either direction of rotation, and means for placing an obstruction in the path of travel of either arm to prevent movement thereof to advance the 90 web.
17. In combination, a web, a pair of spools to which the web is secured and on which it is wound and unwound, a rotatable support on which the web travels, said support including a threaded shaft, means including a pair of arms for driving said support step by step in either direction of rotation, and means for placing an obstruction in the path of travel of either arm to 95 prevent movement thereof to advance the web, said latter means including a pin for each arm, and mechanism for moving the pin into and out of obstructing position, said mechanism including an element adapted to coöperate with the shaft threads.
18. In combination, a web, a pair of spools to which the web is secured and on which it is wound and unwound, a rotatable support on which the web travels, said support including a threaded shaft, means including a pair of arms for driving said support step by step in either direction of rotation, and means for placing an obstruction in the path of travel of either arm to 100 prevent movement thereof to advance the web, said latter means comprising a pair of longitudinally movable rods, pin-carrying levers connected to said rods, an adjustable abutment carried by each rod, and an element threaded to said shaft and movable between said abutments by the rotation of the shaft.
19. In combination, a web, a pair of spools to which the web is secured and on 105

- which it is wound and unwound, a rotatable support on which the web travels, said support including a threaded shaft, means including a pair of arms for driving said support step by step in either direction of rotation, and means for placing an obstruction in the path of travel of either arm to prevent movement thereof to advance the web, said latter means comprising a pair of longitudinally movable rods, pin-carrying levers connected to said rods, an abutment carried by each rod, and an element threaded to said shaft and movable between said abutments by the rotation of the shaft.
20. In an apparatus of the character described and in combination, a web, web-moving means including a rotatable support, means for moving said support step by step in either direction of rotation, a signal, and mechanism for rendering said signal active at predetermined points in the travel of the web, said mechanism including a signal-actuating member, a normally inactive spring for moving said member to actuate the signal.
20. In an apparatus of the character described and in combination, a web, web-moving means including a rotatable support, means for moving said support step by step in either direction of rotation, a signal, and mechanism for rendering said signal active at predetermined points in the travel of the web, said mechanism including a signal-actuating member, a normally inactive spring for moving said member to actuate the signal.
20. In an apparatus of the character described and in combination, a web, web-moving means including a rotatable support, means for moving said support step by step in either direction of rotation, a signal, and mechanism for rendering said signal active at predetermined points in the travel of the web, said mechanism including a signal-actuating member, a normally inactive spring for moving said member to actuate the signal.

nal, a spring-sustained element movable longitudinally and carrying a pivoted lever, means carried by said support for moving said element in one direction and maintaining it in predetermined position, said means being active at spaced intervals during a step travel of the support, said lever and signal actuating member having complementary means for temporary engagement when said element is moved from normal position, return movement of said element placing said spring under tension, and means for breaking the engagement of lever and member during such return travel to render said spring active to move the member to actuate the signal.

In testimony whereof we affix our signatures in the presence of two witnesses.

JOHN C. COCHRAN.
SAMUEL A. WILLIS.
